DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

Continuation of application Ser. No. 729,287, May 15
1968. This application July 30, 1969, Ser. No. 847,822
Int. Cl. G01n 11/04

6 Sheets Drawing. 21 Pages Specification

Apparatus and improved method for continuously determining apparent melt viscosity of a thermoplastic polymer sample wherein the temperature within an extrusion rheometer device is increased at a programmed rate and a transducer, such as a displacement transducer or a linear velocity transducer, continuously senses the displacement or the linear velocity rate of the piston of the rheometer device, and whereby an information receiving device correlates information on actual temperature of the polymer sample and the displacement or linear velocity rate of the piston.
